UNITED STATES PATENT OFFICE.

JOHN H. MORGAN, OF EAST ST. LOUIS, ILLINOIS, ASSIGNOR OF ONE-HALF TO SAMUEL C. JUMP, OF EAST ST. LOUIS, ILLINOIS.

RAIL-JOINT ADJUSTER.

Application filed November 28, 1927. Serial No. 236,325.

This invention relates to rail joint adjusters.

The object of my present invention is to provide a rail joint adjuster, which, in addition to having the desirable features and characteristics of the rail joint adjuster that forms the subject-matter of my pending application for Patent Serial No. 174,206, filed March 10, 1927, is equipped with a novel 10 means for maintaining the rails in accurate longitudinal alignment and permitting them to move freely relatively to each other during the operation of adjusting the rails.

Briefly described, my improved rail joint 15 adjuster consists of two members adapted to be connected to the web of one of the rails in such a way as to embrace the web of the other rail and extend across the joint between the ends of the rails, and a device that 20 is adapted to be forced between an abutment means or surface on one of said members and the edge of a bolt hole in the other rail so as to produce relative longitudinal movement between the rail to which said 25 members are connected and the other rail which said members embrace. The two members of the adjuster, the abutment means on one of said members, and the device that co-operates with said abutment 30 means to produce relative longitudinal movement of the rails, can be constructed in various ways without departing from the spirit of my invention, so long as the elements or parts of the adjuster 35 are of such design that when the adjuster is in use, or is installed in operative position, the meeting ends of the opposed rails will be securely held against lateral movement, but will be capable of moving 40 freely longitudinally relatively to each other and no parts of the adjuster will occupy a position where they will interfere with the tread surface or flange of a wheel that travels over the rails, thereby overcoming 45 the necessity of removing the adjuster and replacing the splice bars or joint members of the track before a car wheel can travel over the two rails that are being adjusted. I prefer to provide one member of 50 the adjuster with a longitudinally adjustable abutment means that can be arranged easily in offset relationship with a bolt hole in the web of the rail that is in opposed relation to the rail to which said member is 55 connected, and provide the other member

of the adjuster that laps over the web of the opposed rail with a horizontally-disposed, elongated slot that forms a clearance for the device which co-operates with the abutment means to produce relative longitudinal movement of the rails. 60

Figure 1 of the drawings is a perspective view, illustrating my improved rail joint adjuster, arranged in operative relationship with two longitudinally-aligned rails that 65 are being adjusted.

Figure 2 is a top plan view, partly in horizontal section, of the structure shown in Figure 1; and

Figure 3 is a view similar to Figure 2, 70 illustrating the method of using the adjuster to produce relative longitudinal movement of a considerable degree, between the rails.

In the drawings which illustrate the preferred form of my invention, A and B designate two longitudinally-aligned rails from which the splice bars, fish plates or rail joint members have been removed, so as to enable said rails to be moved longitudinally relatively to each other to vary the size of 80 the open space or joint α between the terminal ends of the rails, for the purpose of removing or inserting an insulating end post between the rails, or to pull the terminal ends of the rails together or space them 85 farther apart. My improved rail joint adjuster comprises a member C that is adapted to be arranged longitudinally of the rails at one side of the webs of same, and a member E that is adapted to be arranged longitudinally of the rails at the other side of the webs of same, said members C and E being preferably so constructed that they will fit in between the heads and base flanges of the rails and bear against the outer faces 90 of the webs of the rails. Said members are connected to the rail A in any suitable manner, as, for example, by means of bolts 1 that pass transversely through said members and through the web of the rail A, and they are proportioned so that they will extend across the joint between the terminal ends of the rails and embrace the web of the rail B, thereby holding the rails in accurate longitudinal alignment with each other, but permitting them to move freely longitudinally relatively to each other during the operation of adjusting the rails to vary the size of the joint or open space α between the terminal ends of the rails. Usually, one bolt will be 100 105 110

sufficient to retain the member E in operative position, but if desired, the member E can be made of the same length as the member C, and a plurality of bolts can be used for connecting the member C to the web of the rail A. After the members C and E have been installed they virtually form a jaw on the terminal end of one of the rails that embraces the terminal end of the other rail and holds said other rail against lateral movement as effectively as the splice bars or rail joint members that are normally used to maintain the rails in longitudinal alignment with each other.

15 Relative longitudinal movement between the rails A and B, either to increase or decrease the width of the joint between said rails, is produced by driving a tapered device D through a space in the member C and through a bolt hole 2 in the web of the rail B that are arranged slightly offset with relation to each other or disposed in such relation that pressure which said tapered device D exerts on the edge of said bolt hole 25 will produce relative longitudinal movement between the rail B and the members C and E connected to the rail A. So far as my present invention is concerned it is immaterial how the member C is constructed so as to provide an abutment surface or means that is arranged in offset relationship with the bolt hole 2 in the web of the rail B through which the device D is driven. I prefer, however, to provide the member C with an adjustable abutment means that can be set in various positions so as to vary the degree of longitudinal movement imparted to the rail B and also enable said rail to be moved progressively or with a step by step 40 movement relatively to the rail A, said adjustable means being composed of a plurality of shims or filler plates 3 that are mounted in a pocket in the portion of the member C that laps over the web of the rail B, and which are capable of being adjusted longitudinally of said pocket so as to form a transverse space in the member C that is slightly offset with relation to one of the bolt holes in the web of the rail B. 45 When the tapered device D is inserted in said space and then driven into the hole 2 in the web of the rail B, said tapered device will exert pressure on the edge of said bolt hole in a direction tending to move the rail B longitudinally so as to bring the bolt hole 2 in alignment with the transverse space in the member C in which the device D is positioned.

The member E is provided with a horizontally-disposed, elongated opening 4 that registers with or is in horizontal alignment with the bolt holes 2 in the web of the rail B, and which forms a clearance for the device D when said device is forced through the hole 2 in the web of the rail B to pro-

duce relative longitudinal movement between the rails. In the embodiment of my invention herein illustrated the opening 4 in the member E is constructed in the form of an open-ended slot, as shown in Figure 1. 70

To install the adjuster the rail joint members, splice bars or fish plate are first removed from the rails A and B and the rail spikes are removed or loosened sufficiently to permit the rails to move longitudinally 75 of the ties on which they rest. The member C is then arranged on the outside of the rails and the member E is arranged on the inside of the rails, and said members are then securely clamped to the web of the rail A by bolts 1 or in any other suitable way, so as to cause said members to embrace the web of the rail member B and hold said rail B in accurate longitudinal alignment 80 with the rail A. The shims 3 are then adjusted longitudinally of the pocket in the member C so that two of said shims, or one shim and one end wall of said pocket, will be separated by a space that is slightly out of transverse alignment with one of the bolt holes 2 in the web of the rail B. The tapered device D is then introduced into said space with the end of said device projecting into the bolt hole 2 in the web of the rail B, and thereafter said device is driven transversely 85 of the member C, rail B and member E so as to cause said device to exert pressure on the edge of said bolt hole in a direction to produce relative longitudinal movement of the rail B and the members C and E that embrace the web of said rail.

The adjuster is so constructed that no parts of same will be struck by the tread or flange of a passing car wheel, and as the member E co-operates with the member C 105 to securely hold the rail B in longitudinal alignment with the rail A, it is not necessary to remove the adjuster from the rails and replace the splice bars or rail joint members that are normally used to connect the rails 110 together before a train can pass over the track of which the rails A and B form a part. These desirable features, coupled with the fact that the rails A and B are securely held in longitudinal alignment with each 115 other but are capable of moving freely in a direction to increase or decrease the width of the space between the terminal ends of the rails, makes it possible to adjust the rails quickly and without danger of subjecting 120 either rail to an abnormal strain.

Having thus described my invention, what I claim as new and desire to secure by Letters Patent is:

1. A rail joint adjuster, comprising two 125 members adapted to be connected to the opposite sides of the web of one rail and arranged so as to embrace the web of the opposed rail, and a device that is adapted to be forced into engagement with a surface 130

- on one of said members and a surface on said opposed rail located below the tread surfaces of the heads of the rails and disposed so as to produce relative longitudinal movement between the rails.
2. A rail joint adjuster, comprising two members adapted to be connected to the opposite sides of the web of one rail and arranged so as to embrace the web of the opposed rail, an abutment surface on one of said members arranged in offset relation with a bolt hole in the web of the other rail and located below the tread surface of the heads of the rails, and a device that is adapted to be moved transversely of said members and opposed rail, so as to co-operate with said abutment surface and the edge of said bolt hole to produce relative longitudinal movement between the rails.
3. A rail joint adjuster, comprising two members adapted to be connected to the opposite sides of the web of one rail and arranged so as to embrace the web of the opposed rail, a longitudinally-adjustable means on one of said members located below the tread surfaces of the heads of the rails, that forms a space which is arranged in offset relation with a bolt hole in the web of the opposed rail, and a tapered device that is adapted to be driven through said space into said bolt hole so as to produce relative longitudinal movement between the rails.
4. A rail joint adjuster, comprising two members adapted to be connected to the opposite sides of the web of one rail and arranged so as to embrace the web of the opposed rail, an adjustable abutment means on one of said members adapted to be arranged in offset relation with a bolt hole in the web of the opposed rail, an elongated opening in the other member that registers with said bolt hole, and a device that is adapted to be moved into engagement with said abutment means and the edge of said bolt hole so as to produce relative longitudinal movement between the rails.
5. A rail joint adjuster, comprising two members adapted to be connected to the opposite sides of the web of one rail and arranged so as to embrace the web of the opposed rail, a pocket in one of said members located below the tread surfaces of the heads of the rails, a plurality of elements in said pocket that are capable of being arranged in different positions in the pocket so as to form a passageway that is slightly offset with relation to the bolt hole in the web of the opposed rail, and a tapered device that is adapted to be driven through said passageway and bolt hole so as to produce relative longitudinal movement between the rails.
6. A rail joint adjuster, comprising two members adapted to be arranged at the opposite sides of the web of one rail and constructed so as to fit between the heads and base flanges of said rail, means for securing said members to the rail, a slotted portion on one of said members that laps over the web of the opposed rail, a portion on the other member arranged in overlapping relation with the web of said opposed rail and provided with a pocket, a longitudinally-adjustable abutment surface in said pocket, and a device that is adapted to be arranged in engagement with said abutment surface and with the edge of a bolt hole in the web of the opposed rail and then driven transversely of the opposed rail and the portions of said members that embrace said rail.

JOHN H. MORGAN.
